[57] CLAIM

The ornamental design for an auto-pillow, as shown and described.

DESCRIPTION

FIG. 1 is a perspective view of an auto-pillow, showing my new design;

FIG. 2 is a rear elevational view of the design;

FIG. 3 is a bottom plan view of the design;

FIG. 4 is a side elevational view, the opposite side being a mirror image thereof; and,

FIG. 5 is a front elevational view of the design.

The top of the article is flat and unornamented.
